WINDOW CONSTRUCTION

Robert W. McLaughlin, Greenwich, Conn., and
Guy F. Kotrbaty, Bronxville, N. Y.

Application September 10, 1948, Serial No. 48,652

6 Claims. (Cl. 189—73)

1

This invention has to do with a metal window construction. This window construction is particularly adapted for use with construction wall units of the type disclosed in our copending application Serial No. 748,188, filed May 15, 1947.

The window construction of the invention is made of comparatively simple parts which can be produced by the cold roll forming process as well as by other metal forming processes, such as metal extrusion or press processes.

The window unit is single-hung and preferably spring-balanced. Storage space for the entire window unit can be provided in the wall units so as to give a full sash opening. A screen can be attached to one end of the window unit so as to be drawn into and span the window opening as the window is opened and be stored automatically within the wall unit when the window is closed.

The trim elements for the window opening serve as the frame for the sash and provide a sliding track for the sash as well as a side seal for the screen when it is drawn into the window opening. Part of the trim elements are adjustable to permit adjustment of the sliding friction on the sash. The sash is provided with specially shaped flanges which cooperate with the outside trim elements to form weather-tight joints. The sash and trim elements are designed so that they will not extend to any substantial extent into the window opening, thus providing the maximum window space in the window opening.

The trim elements add bearing strength and rigidity to the stud beams of the construction wall unit and as a result the wall units with windows are actually stronger structurally than non-window wall units. This eliminates any restriction on the number of adjoining window wall units that can be used since the entire wall can be of such units without any sacrifice in structural strength.

A preferred form of our window construction unit is illustrated in the accompanying drawings.

Fig. 1 is a view in perspective from the exterior of the window construction installed in a wall unit;

Fig. 2 is a perspective view from the interior of the sash and part of the screen;

Fig. 3 shows an optional detail of the screen, an edge binding to protect the edge and add rigidity to the screen;

Figs. 4 and 5 are vertical cross-sections through the window construction and part of the wall unit above and below the window construction. Fig.

2

4 shows the sash in closed position, and Fig. 5 shows the sash in partly opened position;

Fig. 6 is a horizontal cross-section through the window construction along line 6—6 of Fig. 4. A part of adjoining non-window wall units are shown; and

Figs. 7 to 17 inclusive show in perspective the outline of the various elements forming the sash and trim elements, except that Fig. 10 shows the outline of the portion of the stud beam bordering the window opening.

In the drawings, our window construction is shown applied to a wall construction unit of the type shown in our copending application Serial No. 748,188.

A portion of these wall construction units are shown at the top and bottom of Fig. 6. The wall unit 100 consists of a metal channel with a wall section 102, backed preferably by insulation 101, and stud beams 104. The aligned wall sections 102 of adjoining units form the outside wall surface, and the inner wall surface is formed by the snap-on panel units 106 which may be provided with insulation, as at 107.

To make provision for the installation of our window construction, the wall section 102 is provided with an opening (see Figs. 4 and 5) extending a portion of its length and a substantial portion of its width, leaving a narrow portion 102a of the wall section along the vertical edges of the opening (see center building unit in Fig. 6 and see also Fig. 10). The panel unit 106 is entirely eliminated from the part in alignment with the opening.

The portions of the stud beams exposed by the opening have generally the cross-sectional shape of a channel of which the part 104 constitutes the web and the part 102a one of the flanges. These exposed portions of the stud beams are covered by trim elements 110 and 130 (see Figs. 6, 11 and 13). The outer trim element or reveal 130 has a bent flange 132 which laps the narrow portion 102a and is attached thereto, preferably in a permanent manner as by welding.

The inner vertical edge portion 134 of reveal 130 is indented for purposes to be explained. The inner trim element 110 (see Figs. 6 and 11) has a configuration to fit the inner end of the stud beam 104 and extends towards the indented edge of the outer trim element 130, leaving a vertical slot between their edges which acts as a sliding track for the sash and screen. The edge 114 is preferably bent inward to provide a flat vertical sliding surface for one edge of the track. The inner trim elements 110 are attached to the bent

edges of the stud beam 104 at intervals along their lengths by means of screws 112, which permits adjustment of the sliding friction of the track on the sash and removal of the trim element when it is desired to remove the sash.

The sash frame 20 has vertical edges 120 which have the cross-sectional shape of nested L's (see Fig. 12), the base of the L's mating with the indented portion 134 of the reveal or outer trim element 130 (see Figs. 6, 12 and 13). The upright portion of the larger L 122 engages in the track between the vertical edges 114 and 134 of the vertical trim elements. It will be noted that the insert portion 134 of the outer trim element 130 is about the width of the base of the inner L 124 so that this inset portion provides an additional sliding and aligning surface for the sash and, in addition, the shoulder 132 formed by the inset shields the vertical edge of the sash. The free end of the base of the inner L 124 is turned inward toward the window opening. This bent end may slidingly engage the shoulder 132 so as to assist in keeping the sash in accurate alignment. This bent-in edge also forms an inner shelf to receive mastic 24 for holding the plane 22 in the sash. The overlapping engagement of the vertical sash edge 120 with the indented edge of the vertical trim element 130 presents a series of barriers which provides a weather-tight sliding joint. These parts engage in such a manner that they can be disengaged, on the removal of the inner trim elements, by merely sliding the sash inward.

The lintel of the window opening is partly covered by the channel-shaped head plates 70 and 80 (see Figs. 4, 5, 7 and 8) which are spaced apart a sufficient distance to allow the sash to pass between them. The outer plate 80 has a depending drip cap 82 which may extend at each end beyond head plate 80 so as to span the entire building unit. The head plate 70 extends across the entire width of the wall construction unit 100 and the ends of the head plate 70 are cut away so as to nest around and fit against the stud beam 104. The inner flange of the head plate 70 is shown (see Fig. 4) as overlapping the bottom edge of the snap-on panel 106 and may be attached thereto in a permanent manner, as by welding. When it is desired to remove the sash from the window opening, the head plate can be moved out of the way by removing the snap-on cover 106 from the building unit.

The top edge 90 of the sash frame (see Figs. 4, 5 and 9) is somewhat similar in cross-sectional shape to that of the sash side edges 120. The base of the inner L 94 has a bent edge forming a receiving shelf for mastic. The free edge of the base of outer L 92 has a reversely bent edge forming an upwardly extending grooved cap 96 disposed in line with the inner flange 84 of the outer head plate 80 so that when the sash is in closed position the grooved cap mates with flange 84 to provide a weather-tight seal.

The window sill is partly closed by the sill plates 140 and 160 (see Figs. 4, 5, 14 and 16). As in the case of the head plates, the sill plates are spaced apart to provide a slot or opening in the sill to give access to the storage space in the wall unit covered by the sill plates.

The inner sill plate 160 is generally channel-shaped but its outer flange 162 is bent inwardly to move the rough metal edge out of the path of the screen, to be described. The plate 160, as in the case of the inner head plate, extends across the entire width of the wall unit 100 and the

ends of the plate 160 are cut away so as to fit around the vertical edges of the stud beam 104. Likewise, the inner flange may be attached to the edge of the snap-on panel 106 and the sill plate 160 removed by removal of the snap-on panel from the building unit.

The outer sill plate 140 is pan-shaped with an inner upwardly extending flange or dam 142, and side flanges 144 shaped so as to engage the bottom sides of the outer vertical trim plates 130. The outer edge is bent outwardly and downwardly to form a drip cap 146. This drip cap may extend beyond the sill plate 140 at each end so as to span the entire wall unit.

15 The bottom edge 150 of the sash (see Figs. 15, and 4 and 5) has a ledge portion 154 to hold the pane and retaining mastic, a grooved cap portion 156 and an inwardly extending handle portion 152. The grooved cap portion 156 is in alignment 20 with the dam or upwardly extending flange 142 on the outer sill plate so that when the window is closed (see Fig. 4) these two parts mate to form a weather-tight joint.

25 The screen 172 is clamped to the bottom edge 150 of the sash by means of clamping plate 170, which may be attached by screws 171, for example (see Figs. 17, 2, 4 and 5). The bottom edge of the clamping plate 170 is curved so as to offset the plane of the depending portion of screen 30 172 from the plane of attachment and to bring it in registry with the sliding track formed between the vertical trim elements 110 and 130. The main body of the screen (see Fig. 2) is of approximately the width of the sash so as to span the 35 window opening and extend within said sliding tracks when the window is raised. The outside upper edges of the screen beyond the clamping plate 170 are cut away because this portion of the screen would not be in the plane of said 40 sliding tracks.

The screen 172 may be made of any of the conventional screening materials. These materials usually have sufficient inherent stiffness so that it is unnecessary to frame the screen. However, 45 if desired, greater rigidity can be imparted to the screen by providing an edge binding 174 (see Fig. 3) of any suitable material.

The edges of the screen will slide snugly in 50 said sliding tracks, thus providing a good insect and vermin-proof seal. As the window is raised, the screen is automatically raised to span the window opening, and when the window is closed the screen is automatically lowered into its protected storage position within the wall unit 100. 55 This eliminates wear and tear on the screen due to unnecessary exposure to the elements which occurs when fixed screens are used and also eliminates the need for removing the screens for storage during the winter months since they have their own storage space in situ.

Instead of the conventional weight balance suspension, we prefer to hang the sash by a 60 spring. Ears 126 are placed toward the bottom of the side edges 120 of the sash. The ends of 65 long coiled springs 128 are attached to each ear, and the other ends of the springs are attached to the stud beams 104, in some convenient manner, a substantial distance above the window opening. The force exerted by the spring will 70 counterbalance the weight of the window and tend to urge the window in an upward direction. The friction exerted by the track surfaces formed by the vertical trim elements 110 and 130 will 75 prevent movement of the window under the urging of the springs. The extent of this fric-

tion can be adjusted, as heretofore explained, by loosening or tightening the screws 112 (see Fig. 6).

The ears 126 can be formed by bending up the bottom edge of the larger L 122 of the side sash as shown in Fig. 2. The ears 126 should be placed so as to clear flanges 144 of the outside sill plate when the window is closed.

We claim:

1. In a building structure with a window opening, a metal window construction comprising two vertical trim plates on each side of the window opening, the adjacent vertical edges of said trim plates being spaced apart to form a narrow vertical slot, a sash frame in which each vertical edge has the cross-sectional shape of nested L's with the uprights of the L's disposed substantially in the plane of the sash and with the bases of the L's extending outwardly substantially at right angles to the plane of the sash, the bases of said L's having free ends to receive between them the inner edge of one of the trim plates and providing two flat surfaces in sliding engagement with the trim plate to take care of endwise thrust in either direction and the upright of the larger L engaging in said slot to take care of transverse thrust.

2. In a building structure with a window opening, the window construction as claimed in claim 1, in which the inner vertical edge of each outer trim plate is inset to provide a shoulder which shields the adjoining vertical edge of the sash and serves as a sliding and aligning surface for the free end of the base of the inner L.

3. In a building structure with a window opening, the window construction as claimed in claim 2, in which the free end of the base of the inner L has a flange extending toward the window opening and abutting the shoulder on the inner edge of the outer trim plate.

4. In a building structure with a window opening, the window construction as claimed in claim 3, in which the edge of the inner trim plate forming one wall of the slot is bent laterally to

provide a flat vertical sliding surface on one edge of the slot.

5. In a building structure with a window opening, the window construction as claimed in claim 1, in which each of the inner trim plates are removably mounted to permit removal of the sash frame on removal of the inner trim plates.

6. In a building structure with a window, the window construction as claimed in claim 1, in which each of the inner trim plates are adjustably mounted to permit adjustment of the width of the slot and thus of the frictional engagement of the inner and outer trim elements with the vertical edges of the sash frame.

ROBERT W. MC LAUGHLIN.
